SAFETY SYSTEM FOR ENGINES

Edward Stellingwerf, Remsen, Iowa

Application January 17, 1942, Serial No. 427,208

7 Claims. (Cl. 200—83)

My invention pertains principally to internal combustion engines and the electrical systems of the same.

An object of my invention is to provide safety devices and arrangements in combination with such engines so that in the event that the oil circulation of the engine ceases to operate, the engine will be automatically stopped.

A further object of my invention is to provide means whereby accidental closing of the ignition circuit will not drain the battery of the circuit.

A further object of my invention is to provide an arrangement wherein the safety device will not disconnect the lights of a vehicle to which the arrangement is attached when the vehicle is traveling, in order to prevent undue danger during such conditions.

A further object of my invention is to provide an emergency control arrangement wherein, after the safety device has functioned, the emergency control can be applied for a comparatively short period of time during the desired conditions.

A further object of my invention is to provide all of these combined safety features in a unit mechanism which is positive in operation and requires very few mechanical connections.

A further object of my invention is to provide all of the above features in a simple arrangement which can be manufactured at a reasonable cost.

With these and other objects in view, my invention consists in the construction, arrangement, and combination of the various parts of my device, whereby the objects contemplated are attained, as hereinafter more fully set forth, pointed out in my claims, and illustrated in the accompanying drawing, in which:

Figure 1 is a detailed view of the arrangement with portions thereof being taken in cross section,

Figure 2 is a detail, and

Figure 3 is a schematic diagram of the electrical connections.

I have used the character 10 to designate a cylindrical casing having the top wall 11, a lower wall 12, and side wall 13. Attached to the top wall 11 are the insulating bushings 14 in which are attached the contact members 15 which contact members are attached to the leads 16. Also attached in tight relation to the upper wall 11 is the expansible diaphragm 17 which is of the bellows type. Attached at the bottom of the diaphragm 17 is a spring 18 to which is attached the insulating strip 19, and attached across the strip 19 is the contact bar 20.

A bracket 21 is attached to the casing 10 to support the unit, and communicating with the casing 10 is a further opening 22 which is provided in the angularly positioned shoulder 23 and pivoted at 24 is a small flap 25 which in-

cludes an opening 26 therein. Covering the flap 25 is the protecting housing 27 which includes the larger openings 28 therein. The flap 25 includes a suitable gasket at the bottom thereof. Communicating with the casing 10 is a further reduced diameter chamber 29 in which is peripherally sealed an expansible diaphragm 30 upon which rests the insulating member 31, and attached to the member 31 is the contact bar 32. At the top of the chamber 29 is attached the insulating wall 33 in which is attached the contact prongs 34 to which are attached the leads 35 which leads pass through the casing and are sealed at this point. The insulating wall 33 includes the central opening 36 therein. Communicating with the chamber 29 is the tube 37 which communicates with the oil circulating pump 38 or to any portion of the circulating line.

A further tube 39 communicates through the upper wall 11 of the casing 10 and is attached to the small housing 40 to which is pivoted at 41 a flap valve 42 which includes the small opening 43 therein and which flap valve rests upon the annular shoulder 44. Communicating with the top of the housing 40 is a further tube 45 which communicates with the intake 46 of the engine and the booster pump 47 thereof, and the tube 45 can communicate with either one of these members or both.

Communicating with the tube 39 at 48 is a further tube 49 which communicates at 50 with the hollow casing 51 which includes the substantially conical shaped members 52 and 53 tightly joined at 54. Peripherally attached at 54 is a stretchable diaphragm 55 which bears against the compression spring 56 and also bearing against the diaphragm 55 is the cylindrical plunger 57 which is slidably received within the neck 58 which forms a continuation of the sides 53. The neck 58 includes the flanges 59 which provide attachment to the dashboard 60 of the vehicle.

The plunger 57 includes the emergency indicating means such as 58 thereon. The electrical circuit of the arrangement is shown in Fig. 3 wherein the character 61 indicates the battery, the character 62 the light switch, the character 63 the ignition switch, the character 64 the lighting circuit, and the character 65 the distributor in the ignition circuit. It will be noted that the contact member 32 is in series with the contact member 20. Now that the structure of my device has been explained I shall now explain the operation thereof.

Normally, when there is no condition for emergency use, the plunger 57 is in its outermost position, and not in its inwardly compressed position as shown in Fig. 1. The oil pump 38 of course, always maintains the oil pressure in the tube 31 when the engine is properly lubricating. How-

ever, in the event that the pump does not force oil through the tube 37, which in itself means that the engine is not receiving lubrication, the diaphragm 30 will not be forced into its upward position as shown in Fig. 1, and will be in a collapsed position, with the contact bar 32 thereby breaking the ignition circuit as shown by the wiring diagram, and the battery will therefore fail to supply the proper ignition to the plugs and therefore the engine will cease to operate.

However when the engine is running, the intake member 46 or the booster pump 47 in applying suction to the tubes 39 and 45 will cause the flap valve 42 to open upwardly the suction of which is sufficient to collapse the bellows member 17, or to carry the bottom of the bellows member upwardly so that the bar 20 makes contact across the prongs 15. However in spite of the fact that the connection is made at this point, since the lower bar 32 is in series therewith, the ignition will cease to operate and the motor will stop. This then, prevents undue eroding and unlubricated wear of the pistons against the cylinder walls, thereby preventing deterioration of the engine.

This feature also provides a further feature in order to protect the drivers of the vehicle during night driving, since in case the vehicle were driving at a rather rapid rate, even if the ignition fails due to the absence of the oil pressure, the suction applied from the engine will maintain the lights in the circuit so that the lights are always on as long as the engine is turning over.

For a further condition, assuming that the automobile is in the garage and the motor is not running or pumping oil, and it is desired to use the lights of the vehicle, the plunger member 51 is then employed. In this case the face of the plunger is pressed inwardly, carrying the plunger into the position as shown in Fig. 1 thereby forcing the diaphragm 55 and spring 56 inwardly, wherein the air in the casing 51 will be forced downwardly through the tube 49 and upwardly through the tube 39 opening the valve 42.

Next the valve 42 will fall to its natural position, thereby creating a partial vacuum within the bellows 17, the suction effect of which will draw the contact 20 upwardly against the contacts 15 with the bellows 17 then being in a compressed or collapsed position. The normal position of the bellows is shown in Fig. 1 or in its expanded condition, and the walls thereof have sufficient resiliency in order to maintain it in expanded position during normal conditions of pressure on both sides of the bellows.

This causes the lights to operate, and it will be noted that the small opening 43 will cause the air to be drawn slowly downwardly back into the bellows 17 until the normal pressure is then inside of the bellows with relation to the outside, and the contact bar 20 will break away from the prongs 15, thereby breaking the circuit. This then provides an emergency means for supplying lights for a short duration of time, assuming of course that the light switch 42 has also been operated.

A further effect is also obtained by means of the emergency arrangement, in closing the ignition circuit at the same time as the light circuit is applied. This feature is important, especially in those cases wherein after the ignition circuit has been broken through absence of oil pressure, it is desired to run the vehicle to a garage or location where the oil supply can be replenished or the mechanism repaired.

For this effect, the operation effecting the bar 20 of course occurs at the same time as explained above, and when the bellows 17 collapses, the reduction in volume thereof will correspondingly cause a partial vacuum to be formed in the chamber 10 surrounding the bellows. This partial vacuum will have the tendency of drawing the diaphragm 30 upwardly thereby carrying the contact bar 32 into engagement with the prongs 34, and since the bar 20 is in engagement, the ignition circuit will be then completed, so the vehicle can then be operated for a short period of time until the air entering through the small opening 26 of the valve 25 reestablishes a normal pressure inside of the casing 10.

It will be noted that the opening 36 permits the partial vacuum to operate on the diaphragm 30. The spring 18 insures that the bellows 17 can collapse to a rather substantial degree and return to open position and still maintain the contact 20 for the maximum interval. The valve 25 is pivoted as shown, so that at a certain point in the downward travel of the bellows 17 it will allow the air in the chamber 10 to escape a little more rapidly, however up to this point the vacuum in the chamber 10 will assist in keeping the valve 25 in closed position.

It will be noted from the foregoing description that even if the ignition contact switch at 62 is accidentally left on, the battery cannot drain inasmuch as the oil pressure is not then applied when the engine is not running since the contact bar 32 will not contact the prongs 34. Similarly the light switch 62 if left on will not allow the lights to operate since if the engine is not running the bar 20 will not allow the circuit to close inasmuch as contact is not established across the prongs 15.

It will therefore now be seen from the foregoing that I have provided all the objectives contemplated in my invention with other advantages being readily apparent.

Some changes may be made in the construction and arrangement of the parts of my invention without departing from the real spirit and purpose of my invention, and it is my intention to cover by my claims any modified forms of structure or use of mechanical equivalents which may be reasonably included within their scope.

I claim as my invention:

1. In combination with a source of pressure and an electrical circuit, diaphragm means for breaking the electrical circuit when the source of pressure is not operating, including a pair of contacts in said electrical circuit, a contact bar for bridging said contacts, said contact bar being attached to the diaphragm, an emergency control for bridging said contacts upon failure of the source of pressure, said emergency control adapted to provide a partial vacuum above the diaphragm.
2. In combination with a source of pressure and an electrical circuit, diaphragm means for breaking the electrical circuit when the source of pressure is not operating, including a pair of contacts in said electrical circuit, a contact bar for bridging said contacts, said contact bar being attached to the diaphragm, an emergency control for bridging said contacts upon failure of the source of pressure, said emergency control adapted to provide a partial vacuum above the diaphragm, said emergency control including a chamber, an expansible bellows within said chamber, a tube communicating with said bellows, a further chamber communicating with said tube

and including a stretchable diaphragm therein whereby release of said diaphragm after pressure thereagainst will cause a vacuum to be formed in said bellows, the collapsing of which will form a partial vacuum in said chamber.

3. In combination with a source of pressure and an electrical circuit, diaphragm means for breaking the electrical circuit when the source of pressure is not operating, including a pair of contacts in said electrical circuit, a contact bar for bridging said contacts, said contact bar being attached to the diaphragm, an emergency control for bridging said contacts upon failure of the source of pressure, said emergency control adapted to provide a partial vacuum above the diaphragm, said emergency control including a chamber, an expansible bellows within said chamber, a tube communicating with said bellows, a further chamber communicating with said tube and including a stretchable diaphragm therein whereby release of said diaphragm after pressure thereagainst will cause a vacuum to be formed in said bellows, the collapsing of which will form a partial vacuum in said chamber, means for forcing said stretchable diaphragm including a plunger member engaged thereagainst.

4. In combination with the source of pressure and an electrical circuit, diaphragm means for breaking the electrical circuit when the source of pressure is not operating, including a pair of contacts in said electrical circuit, a contact bar for bridging said contacts, said contact bar being attached to the diaphragm, an emergency control for bridging said contacts upon failure of the source of pressure, said emergency control adapted to provide a partial vacuum above the diaphragm, said emergency control including a chamber, an expansible bellows within said chamber, a tube communicating with said bellows, a further chamber communicating with said tube and including a stretchable diaphragm therein whereby release of said diaphragm after pressure thereagainst will cause a vacuum to be formed in said bellows, the collapsing of which will form a partial vacuum in said chamber, means for forcing said stretchable diaphragm including a plunger member engaged thereagainst, a further tube communicating with said tube including an upwardly opening valve, said further tube communicating with a source of suction, said valve having a small opening therein.

5. In combination with a source of pressure and an electrical circuit, diaphragm means for breaking the electrical circuit when the source of pressure is not operating, including a pair of contacts in said electrical circuit, a contact bar for bridging said contacts, said contact bar being attached to the diaphragm, an emergency control for bridging said contacts upon failure of the source of pressure, said emergency control adapted to provide a partial vacuum above the diaphragm, said emergency control including a chamber, an expansible bellows within said chamber, a tube communicating with said bellows, a further chamber communicating with said tube and including a stretchable diaphragm therein whereby release of said diaphragm after pressure thereagainst will cause a vacuum to be formed in said bellows, the collapsing of which will form a partial vacuum in said chamber, means for forcing said stretchable diaphragm including a plunger member engaged thereagainst, a further tube communicating with said tube including an upwardly opening valve, said further

tube communicating with a source of suction, said valve having a small opening therein, said chamber including an outwardly opening valve member having a small opening therein to provide a partial vacuum in said chamber during certain time limits.

6. In combination with a source of pressure and an electrical circuit, diaphragm means for breaking the electrical circuit when the source of pressure is not operating, including a pair of contacts in said electrical circuit, a contact bar for bridging said contacts, said contact bar being attached to the diaphragm, an emergency control for bridging said contacts upon failure of the source of pressure, said emergency control adapted to provide a partial vacuum above the diaphragm, said emergency control including a chamber, an expansible bellows within said chamber, a tube communicating with said bellows, a further chamber communicating with said tube and including a stretchable diaphragm therein whereby release of said diaphragm after pressure thereagainst will cause a vacuum to be formed in said bellows, the collapsing of which will form a partial vacuum in said chamber, means for forcing said stretchable diaphragm including a plunger member engaged thereagainst, a further tube communicating with said tube including an upwardly opening valve, said further tube communicating with a source of suction, said valve having a small opening therein, said chamber including an outwardly opening valve member having a small opening therein to provide a partial vacuum in said chamber during certain time limits, the opening in said upwardly opening tube valve providing further means for providing a partial vacuum in said bellows during certain time limits.

7. In combination with a source of pressure and an electrical circuit, diaphragm means for breaking the electrical circuit when the source of pressure is not operating, including a pair of contacts in said electrical circuit, a contact bar for bridging said contacts, said contact bar being attached to the diaphragm, an emergency control for bridging said contacts upon failure of the source of pressure, said emergency control adapted to provide a partial vacuum above the diaphragm, said emergency control including a chamber, an expansible bellows within said chamber, a tube communicating with said bellows, a further chamber communicating with said tube and including a stretchable diaphragm therein whereby release of said diaphragm after pressure thereagainst will cause a vacuum to be formed in said bellows, the collapsing of which will form a partial vacuum in said chamber, means for forcing said stretchable diaphragm including a plunger member engaged thereagainst, a further tube communicating with said tube including an upwardly opening valve, said further tube communicating with a source of suction, said valve having a small opening therein, said chamber including an outwardly opening valve member having a small opening therein to provide a partial vacuum in said chamber during certain time limits, the opening in said upwardly opening tube valve providing further means for providing a partial vacuum in said bellows during certain time limits, said bellows including a contact bar therein, resilient means supporting said bar, a pair of prongs adapted to contact said contact bar upon collapse of said bellows.
